UNITED STATES PATENT OFFICE.

JOSEPH WILLIAMS, OF MENLO PARK, CALIFORNIA.

CLOTHES-PIN.

SPECIFICATION forming part of Letters Patent No. 245,039, dated August 2, 1881.

Application filed March 5, 1881. (No model.)

To all whom it may concern:

Be it known that I, JOSEPH WILLIAMS, of Menlo Park, in the county of San Mateo and State of California, have invented a certain 5 new and useful Clothes-Pin, of which the following is a specification.

The object of my invention is to provide a clothes-pin that will be simple and cheap in construction, and one that can be easily adjusted and will securely hold the clothes to the line. I accomplish this object by the device illustrated in the accompanying drawings, in which—

Figure 1 is a top view. Fig. 2 is a side elevation. Fig. 3 is a vertical section. Fig. 4 is a perspective view, showing the clothes-pin applied to a clothes-line.

Similar letters indicate like parts throughout the several views.
20 A is the body of my clothes-pin, which has a hole, B, bored transversely through it, and provided with a countersunk portion at one side, in which to receive the elastic tie or holder of which my clothes-pin is composed.
25 The elastic holder C is composed of a strip of india-rubber formed into a loop, which is drawn through the hole or opening in the

wooden body of the pin and confined by a knot in the countersunk portion of the hole.

In practice the clothes are put or spread upon the line in the usual manner, and the pin, with the loop forward, is placed against the line at each corner of the article and the loop passed around the article to be dried or confined and the end of the loop brought over upon the head of the pin, which closely confines the article until it is dried.

Having thus described my invention, what I claim, and desire to secure by Letters Patent, is—

A wooden clothes-pin provided with a head and elastic loop adapted to be passed around the line and article to be dried and confined in position by bringing the loop over the head or body of the pin, in the manner substantially 45 as herein set forth and specified.

In testimony that I claim the foregoing I have hereunto set my hand and seal this 15th day of February, 1881.

JOSEPH WILLIAMS. [L. S.]
